UNITED STATES PATENT OFFICE.

THOMAS W. HOLT, OF ELKHART, INDIANA, ASSIGNOR, BY MESNE ASSIGNMENTS, TO THE ADAMS & WESTLAKE COMPANY, OF CHICAGO, ILLINOIS, A CORPORATION OF ILLINOIS.

SASH GUIDE.

Original application filed May 25, 1925, Serial No. 32,537. Divided and this application filed October 9, 1926. Serial No. 140,541.

The purpose of this invention is to provide an improved sash guide of the type adapted to fit within a grooved sash stile, which guide is light, durable and inexpensive, and is designed to function as a weather strip and a lock rack as well as a guide.

One form of the invention is presented herein for the purpose of exemplification, but it will of course be appreciated that the invention is susceptible of embodiment in other slightly modified forms characterized by the same advantageous features.

In the accompanying drawing:

Fig. 1 is a view of a corner of a window sash associated with a guide constructed in accordance with the invention;

Fig. 2 is a front view of the guide;

Fig. 3 is a side view of the same; and

Fig. 4 is a transverse section, taken on the line 4—4 of Fig. 3.

As will be observed in the drawing, the guide is attached to a window jamb 10, and is embraced between the side walls 11 of a guide groove in the outer margin of a sash stile 12. The guide consists essentially of two channel strips 13 and 14, which are arranged one within the other. The guide may also include a lock rack 15 in the form of a plurality of integrally associated lock stops 16.

The strip 13 is of U-shaped cross section, and is rigid, being formed of relatively thick sheet metal. The strip 14 is also of U-shaped cross section, but is resilient, being formed of relatively thin sheet metal. The base 17 of the strip 13 is secured contiguously against the window jamb 10, and the strip 14, which is smaller, is nested within the strip 13, with the base 18 of the strip 14 against the base 17 of the strip 13. The sides of the strip 14 project from the channel in the strip 13, and are flared laterally at 19 in opposite directions beyond the sides of the strip 13 for resilient engagement with the side walls 11 of the groove in the stile. The flared marginal portions 19 may also engage resiliently with the base of the groove in the stile. The portions 19 of the strip 14 are preferably of U-shaped cross section in order to provide relatively broad and frictionless bearing beads for sliding coaction with the wall of the groove in the

stile, but it will of course be appreciated that such portions may be of any other desired cross section. The strip 13 is of slightly less width than the groove in the stile, and the side walls 11 of the groove are normally maintained in spaced relation to the side walls of the strip 13 by the resilient action of the projecting portions 19 of the strip 14. The strip 14, when uncompressed by the side walls 11 of the groove is of slightly greater width across the portions 19 than the groove.

The lock rack 15 is a flat strip which is secured in the channel in the strip 14 against the base 18 of the same and is bent outwardly at intervals to provide stops 16 having horizontal upper surfaces 20 and inclined under surfaces 21. The strips 13 and 14 and the lock rack 15 are permanently secured together by a plurality of rivets 22, and the resulting combination guide, weather strip and lock rack structure is detachably secured against the window jamb 10 by a plurality of screws 23.

From the foregoing description, it will be appreciated that the guide of the invention is extremely simple in construction, is inexpensive to manufacture, is easy to apply, and is efficient in operation as a guide, a weather strip and a lock rack.

This application is a division of my co-pending application Serial No. 32,537 filed May 25, 1925.

I claim:

1. The combination with a sash having a groove in the stile thereof, of a guide comprising two channel strips arranged one within the other to form in effect a rib for insertion within the groove, the inner strip having a resilient portion projecting from the contour of the outer strip for resiliently yieldable engagement with the sash at a point within the groove.

2. A sash guide comprising two channel strips arranged together in nested relation, the inner strip having a resilient marginal portion projecting from the outer strip throughout the length thereof for resiliently yieldable engagement with a cooperating sash portion.

3. A sash guide comprising two channel strips arranged together in nested relation,

the inner strip being resilient and having the marginal portions thereof projecting from the outer strip throughout the length thereof for resiliently yieldable engagement with cooperating sash portions.

4. A sash guide comprising a rigid channel strip of relatively thick sheet metal, and a resilient channel strip of relatively thin sheet metal secured within the rigid strip and having its marginal portions projecting beyond those of the rigid strip for resiliently yieldable movement toward the latter.
5. A sash guide comprising a rigid channel strip of relatively thick sheet metal, and a resilient channel strip of relatively thin sheet metal secured within the rigid strip

and having its sides flared laterally in opposite directions beyond the rigid strip for resiliently yielding movement toward the same.

6. A sash guide comprising a rigid strip, a resilient strip secured to the rigid strip and having a portion projecting laterally beyond such strip for resiliently yielding movement toward the same, and another rigid strip secured to the first mentioned rigid strip and the resilient strip and bent laterally at intervals throughout the length thereof to provide a plurality of lock stops.

In testimony whereof I have hereunto subscribed my name.

THOMAS W. HOLT.
